UNITED STATES PATENT OFFICE

CHARLES P. THOMPSON, OF WESTMONT, NEW JERSEY, ASSIGNOR TO WILLIAM S. SCULL COMPANY, OF CAMDEN, NEW JERSEY, A CORPORATION OF NEW JERSEY

DESIGN FOR A BAG OR SIMILAR CONTAINER

Application filed April 28, 1932. Serial No. 43,651. Term of patent 7 years.

To all whom it may concern:

Be it known that I, CHARLES P. THOMPSON, a citizen of the United States of America, residing at Westmont, in the county of Camden, State of New Jersey, have invented a new, original, and ornamental Design for a Bag or Similar Container, of which the following is a specification, reference being had to the accompanying drawing, forming part thereof.

The figure is an elevation of a bag or similar container, showing my new design.

The bag is flat, of conventional form, and the dominant feature of the design is the ornamentation appearing on the face of the article. Such ornamentation may appear on one face only of the article.

I claim:

The ornamental design for a bag or similar container as shown and described.

CHARLES P. THOMPSON.
